DESIGN FOR A SMOKING PIPE

Clarence W. Booker, San Diego, Calif.

Application August 2, 1948, Serial No. 147,880

Term of patent 14 years

(Cl. D85—8)

To all whom it may concern:

Be it known that I, Clarence W. Booker, a citizen of the United States of America, residing at San Diego, in the county of San Diego and State of California, have invented a new, original, and ornamental Design for Smoking Pipe, of which the following is a specification, reference being had to the accompanying drawings, forming a part thereof.

Fig. 1 is a top, plan view of a smoking pipe showing my new design; Fig. 2 is a side elevational view thereof; Fig. 3 is a sectional view taken from the line 3—3 of Fig. 2; and Fig. 4 is a sectional view taken from the line 4—4 of Fig. 2.

I claim:

The ornamental design for a smoking pipe, substantially as shown.

CLARENCE W. BOOKER.
